UNITED STATES PATENT OFFICE

2,093,208

METHOD OF MAKING SHEET METAL PILING

Karl Nolte, Dortmund, Germany, assignor to
Dortmund-Hoerder Huttenverein Aktiengesellschaft, Dortmund, Germany

Application April 5, 1934, Serial No. 719,181
In Germany March 16, 1931

5 Claims. (Cl. 29—155)

There is described in the United States Patent No. 1,841,779 sheet piling, in which flanged I-sections are inserted into flat piling and welded thereto. This construction was selected in order to facilitate production and at the same time to secure a more effective distribution of the metal; it has, however, the disadvantage that the section with two flanges must be inserted into the metal sheet in the longitudinal direction and then welded thereto. The duplication of work and the accumulation of metal at the flange involves unnecessary expense.

According to the invention this disadvantage is avoided by providing a sheet piling wall consisting of sections of T-form having relatively wide flanges in which the flanges are formed by a single metal sheet welded or otherwise secured to the web of a T-section having relatively small flanges.

The accompanying drawing illustrates diagrammatically in cross-section several constructions of the sheet piling wall according to the invention.

In Figure 1 the metal sheet *c* advantageously of iron which carries the locking or claw members *a* and the shoulder or flange *b* is welded at *d* to the web *e* of a T-section *f* having relatively small flanges.

A particularly simple construction is illustrated in Figure 2 in which locking parts *i* are provided in known manner for connecting together the sections forming the wall, as in this way the joining by rolling, of the metal sheets by the locking parts, which may be of similar construction, is greatly facilitated.

The sheet of iron *g* is provided at its ends with locking parts *h*, *h*, which parts are of similar construction, over which a locking part *i* is passed for connecting the adjacently disposed plates of iron before the pile-driving or ramming operation. The sheet of iron *g* is provided with a short web-like extension *k* which is welded at *l* to the web *m* of a T-section, the web being provided at the other end with the heavier but relatively smaller flanges *n*.

According to Figure 3 the metal plate *g* is pro-

vided with two lugs *o* on the inner side of the plate to serve as guides for the web *e* of the T-section having relatively wide flanges so that assembling for welding is much facilitated, as no additional means are necessary for straightening up or clamping the web *e* in position.

A further known advantage is afforded by the fact that the lugs can be used for welding purposes when welding with gas or electric welding without the use of any additional substance, so that thus the welding operation is considerably simplified.

It will be understood that the web *m* (Figure 2) may be provided at its free end with a channel for receiving the extension *k*.

I claim:

1. A method of producing units of sheet piling with non-uniform flanges from sheets of metal strengthened by elements of rolled section disposed normal to the said sheets, consisting in 20 rolling a sheet of metal to the form of a thin flange forming along the lateral edges locking parts for the engagement of similar flanges of adjacent units, rolling a thick flange in a single piece with a symmetrically disposed web of small 25 thickness, and finally joining the said web to the thin flange by welding at a position intermediate the length of the said thin flange.

2. A method according to claim 1, consisting in 30 positioning the thin flange symmetrically to the plane of the web and to the locking parts.

3. A method according to claim 1, consisting in 35 rolling in the thin flange, an intermediate web of small depth, and welding the said web with the web rolled with the thick flange.

4. A method according to claim 1, consisting in 40 rolling the thin flange with a pair of laterally disposed spaced ribs and in welding the web of the thick flange between the said ribs.

5. A method according to claim 1, consisting in 45 rolling the thin flange with a pair of laterally disposed spaced ribs and in welding the web of the thick flange between the said ribs, the said ribs serving as welding material for effecting the weld to the said web.

KARL NOLTE.
